Primary Examiner—Janice E Seeger

(74) *Attorney, Agent, or Firm*—Angela Holt; Lanier Ford Shaver & Payne P.C.

(57) **CLAIM**

I claim the ornamental design for a portable folding craft table with storage, as shown and described.

DESCRIPTION

(63) Continuation of application No. 11/408,095, filed on Apr. 20, 2006.

FIG. 1 is a perspective view of a portable folding craft table with storage according to the present invention.

(51) **LOC (9) Cl.** **06-03**
(52) **U.S. Cl.** **D6/429; D6/487**

FIG. 2 is a top view of the portable folding craft table with storage according to the present invention shown with the tabletops in an open position and with the legs stowed.

(58) **Field of Classification Search** D6/480-489,
D6/429-431, 511, 397, 398; 108/150, 152,
108/153.1, 157.1, 161, 25, 26, 33, 34, 36,
108/38, 90

FIG. 3 is a bottom view of the portable folding craft table with storage according to the present invention shown with the tabletops in a closed position and the work shelf in the open position.

See application file for complete search history.

FIG. 4 is a side view of the portable folding craft table with storage according to the present invention with the tabletops in a closed position and with the legs stowed.
